UNITED STATES PATENT OFFICE

THOMAS AUGUSTUS DRING, OF RINGWOOD, ENGLAND

FLYING MACHINE

Application filed June 6, 1929, Serial No. 368,841, and in Great Britain June 14, 1928.

The present invention deals with improvements in flying machines whereby such machines may be caused to rise or descend in a vertical plane, sustained in the air, and also moved in a horizontal plane.

According to the present invention there is provided a method of lifting or sustaining a flying machine by the expansive force of opposing streams of compressed air produced by 10 non-feathering rotary propellers arranged well towards one end of the body of the machine, said streams acting on the underside of the body and/or other supporting surfaces 15 of the machine and producing a resultant acting through the centre of gravity of the machine.

For lifting, or lifting and hovering flight, the forces acting are so arranged as to give no resultant in line with the longitudinal axis 20 of the machine, but for horizontal flight such a resultant may be given as, by way of example, hereinafter appears.

One important feature of this invention is that the same mechanism which produces the 25 streams of air that give a vertical component to support the machine may also be used to produce backward or forward motion.

The machine is supported in the vertical plane by forces acting in an upward direction 30 on the under side of the body, the resultant of which passes upwards through the centre of gravity, an even keel being maintained by the sum of the moments of these forces, acting to the rear of the centre of gravity, being equal 35 to the sum of the moments acting to the front of the centre of gravity.

When, in order to travel forward, the fans or revolving wings are thrown forward, the 40 angle of the air currents passing under the body to the rear of the centre of gravity becomes more acute with respect to the longitudinal axis of the machine, and, consequently, less powerful, but the resultant of the 45 forces is applied at a greater distance from the centre of gravity. Conversely, the air currents in front of the centre of gravity becomes less acute, and therefore give a more powerful resultant which is applied however nearer to 50 the centre of gravity.

The components of the moments alone are altered, but the moments remain the same.

The effect of the meeting of the two streams of compressed air is to produce a pressure at the place of meeting greater than the normal. 55 Further the air will expand from the neighbourhood of this place and uprushing streams will impinge on the underside of the body and/or wings of the machine. In some cases these streams rushing upwards past the sides 60 of the body may produce by induction a decrease of pressure above the body and/or planes.

As many embodiments of the present invention may be made and as the parts herein described may be varied in many ways, it is to be understood that all matter herein set forth or shown in the accompanying drawings is to be interpreted as illustrative and not 65 in a limiting sense.

In the drawings:

Fig. 1 is a front elevation, Fig. 2 a side elevation with the vanes turned clockwise through 45° with respect to Fig. 1, and Fig. 3 70 a plan view of the machine.

Figs. 4 and 5 are respectively elevation and plan of the port side fans or vanes, and Figs. 6 and 7 similar views of the starboard side fans or vanes.

Fig. 8 is a diagrammatic view indicating in 75 full lines the cone produced for forward flight, in dotted outline for hovering or lift, and in Morse lines for backward flight.

Figs. 9, 10 and 11 are views of the crown 80 wheels hereinafter referred to.

Figs. 12 and 13 illustrate the control devices for the crown wheels and allied parts.

Fig. 14 shows a drive for the fans or vanes 85 each fan having its own engine.

According to one way in which it is proposed to carry out the present invention a revolving shaft 1 is mounted transversely of the body of the aircraft to extend on opposite sides thereof, and so disposed as to lie at right-angles to both the longitudinal axis 90 and the vertical axis of the body of the machine.

On the opposite projecting ends of this shaft are vanes which produce and discharge 95 opposing streams of compressed air whose ki- 100

netic energy is in part destroyed on mutual impact thereby producing a lifting force.

The machine is supported in the air by the expansive force of opposing streams of compressed air in the form of truncated cones produced by the blades or vanes 2, which streams are intercepted beneath the fuselage of the machine.

The stream producing means shown take the form of a plurality of non-feathering blades or vanes 2 arranged well toward one end of the body.

The fan shafts 3 as shown are arranged so as to be adapted to be moved forward together, but they might be arranged so that one could be advanced somewhat farther forward than the other, for steering purposes. Lifting or hovering flight is produced when the axes of the fans are co-axial with the axis 20 of the revolving shaft 1 as shown in Fig. 9, an inclination of the fan shafts forwardly produces forward flight, and an inclination rearwardly backward flight, the machine being sustained during these flights.

Steering by a vertical rudder may also be adopted, and this method of steering is shown, the rudder being indicated by the reference numeral 4.

The body of the machine as shown is provided with planes or sustaining surfaces 5 and 6 located behind and/or above the rotary fans 2 and similar sustaining surfaces may extend longitudinally of the machine in order to obstruct the air streams which may be diverted longitudinally beneath the body.

One way of driving the revolving shaft 1 may be as follows:

Each end of the shaft 1 passes through a bearing into a hinged casing 7 where it terminates in a crown wheel 8. Crown wheels 9 meshing with the crown wheels 8 are attached to the shafts 3 and passing through similar bearings in the same casing 7.

When all four crown wheels are fully in mesh, and the casings closed, the three shafts will be in the same straight line, and the crown wheels will revolve as solids. This is the hovering or lifting flight position. Hovering is maintained by regulating the pressures of the streams in balanced relationship to the force of gravity.

For forward flight the outer covers of the crown wheel casings, which are hinged, are opened by levers hereinafter referred to applied from the cockpit, and carry with them the short fan shafts and fans. The crown wheels are then still in mesh on one side of their circumference, and are consequently driven at an angle with the central shaft.

The engine may be mounted in any suitable position and the engine shaft, which may be provided with a clutch, carries a worm meshing with a worm wheel at the centre of the transverse shaft 1.

As stated each pair of crown wheels runs in

a hinged casing, or circular box, the inner half of which provides bearings for one end of the transverse shaft, and the outer half bearings for the fan shaft.

The outer half of each casing is free to swing forward in the horizontal plane to the extent of 30 or 40 degrees or thereabouts, the movement being controlled by a radius rod 10 from the surface of a disc 11 or cross head or the equivalent capable of a partial rotation in the vertical plane, and actuated from the cockpit by a hand-wheel 12 and worm 13, the latter meshing with a worm-wheel 14 on the axis of the cross-head or disc or the like.

When all four crown wheels are in full mesh, the central transverse shaft and the two fan shafts are in the same straight line and the crown wheels revolve as solids.

In this position the machine is lifted and sustained in the vertical plane by an increase of atmospheric pressure against the lower part of the body (assisted it may also be by a reduction of the pressure above) due to the mutually intercepting streams or intercepted streams of compressed air below the body of the machine.

The forces produced by reaction against the surfaces of the vanes from the inertia of the air, which gives resultants acting outwardly in line with the rotating shafts neutralize one another. This is the hovering position.

These latter forces are brought into play by swinging open the crown wheel cases and thus obtaining a second resultant in line with the long axis of the body of the machine, which serves to draw the machine forward.

This is done without in any way reducing the forces sustaining the body of the machine.

In shape the vanes of the revolving fans may follow broadly the contours of the wings of such a hovering insect as the common drone-fly (*Eristalis tenax*), and may be affixed at their bases to the surfaces of a triangular or quadrangular pyramid 15, the inner edge of each wing vane being flush with the edge of the side of the pyramid, but the outer edge projects beyond the opposite edge. Each vane, therefore, projects over the one below.

The angle which the outer edge of the vane makes with the shaft determines, to some extent, the angle of the truncated cone formed by the outflowing currents of air, but this is also affected by the angular velocity.

The angle at the apex of the pyramid by determining the outward inclination of the surface of the vane, determines also the force of the thrust, or "attack", against the air, and the direction of its reaction. The stronger the attack the less favourable the direction of its reaction and vice versa.

The angle of the conical path swept by the outer edges of each vane when rotating is about 35° with the axis of rotation, but ex-

periment would be necessary to determine the optimum form for any machine.

With all vertical flight machines there is danger should engine trouble occur. With 5 the type shown the revolving fans will afford some assistance and if the centre of pressure is vertically in line with the centre of gravity the machine will tend to fall on an even keel. I have also shown in Fig. 3 an expanding or 10 fan-like tail 16 to enable a pilot to plane down in a spiral in the event of engine failure. In ordinary flight the tail is closed. The expansion of the tail by shifting the centre of pressure a little more to the rear, gives the 15 machine a downward inclination.

With two engines the risk of engine failure is enormously reduced, provided that the machinery is so arranged that either engine can drive both fans in the event of its fellow 20 being put out of action. This can be arranged as follows, and is shown in Fig. 14.

Each of the two engines 17 and 18 is secured to a small platform, or bracket 19, capable of turning through an arc of 30 or 35 25 degrees in the horizontal plane about a vertical spindle 20 attached to the outside of the body of the machine. Each fan shaft 3 is carried on bearings 21 supported by such spindle and bracket. To the inner end of 30 each fan shaft 3 is attached a crown wheel 22 of special form which, when the two fan shafts 3 are in the same straight line, lightly meshes with the corresponding crown wheel on the other shaft. In this position the two 35 crown wheels revolve as a solid, each fan being driven by its own engine, and the speeds of both engines being synchronized by the coupling. The drives from the engines are through worms and worm-wheels, the latter 40 being mounted on free-wheel clutches. The drives are indicated generally by the reference 23.

The two engine platforms 19 are controlled by radius rods 24 from the cockpit by a hand-wheel and worm-wheel in a similar way to that shown in Figs. 12 and 13, which enable the pilot to draw towards him the two platforms, with all the machinery mounted thereon and thus throw forward the fans carried 50 on the outside of the vertical spindles. This action gradually draws the crown wheels out of mesh, but sufficient of the teeth on one side of each wheel remains in mesh to carry on 55 the drive up to an angle of 35 degrees. At a lesser angle the wheels are more closely engaged. Should either engine fail the wing shaft that it had been driving would automatically take its drive from the other engine 60 through the crown-wheel couplings.

The rotating fans are made right-hand and left-hand and are not interchangeable. Their motion as shown is:—

Starboard side—clockwise.

65 Port side—anti-clockwise.

They will not reverse or operate in the contrary direction.

The vanes may correspond to an aerofoil or flat board like form or more conforming to portions of planes than to the more usual parts of helicoidal surfaces, or they may increase in pitch towards the boss and diminish in pitch towards the tips like or similar to a true pitch propeller. The vanes or blade may also be made concave towards the machine, or/and convex away from the machine, or/and as a straight-faced or true-pitch blade or as an increasing-pitch blade to increase the angle of attack of the following part of the blade.

Fixed wings or planes are not absolutely essential, but may be added for (a) to provide sufficient area to enable the craft to descend in safety in case of engine trouble, (b) in the case of the lower plane to supplement the area subject to air pressure, and in the case of the upper plane to cut off any rising currents of air.

The centre of pressure on the under side of the body as well as the mean centre of pressure on the two fixed planes will be some little distance to the rear of the transverse shaft carrying the fans or vanes. The centre of gravity will be so arranged that it is in a vertical line with and between the mean 90 centres of pressure.

Cooling of the engines may be by way of air ports in the sides of the body, and by gratings in the roof of the engine chamber through which the fans will create a circulation of cold air.

In both constructions described the control of the drives provides for slow backward flight, as well as hovering and forward flight.

It is to be understood that bracing systems will be provided at any necessary parts of a machine.

What I claim is:—

1. Apparatus for lifting or sustaining a flying machine by the expansive forces produced by mutual impact of opposing streams of compressed air, comprising non-feathering propellers arranged well towards one end of the body, mountings therefor, each propeller consisting of a plurality of blades rotating about a fixed axis with the inner and outer edges of the blades sweeping through conical paths so as to produce streams of compressed air, which streams are opposed in pairs and create expansive forces by mutual impact beneath the fuselage of the machine, means for rotating said propellers, and means for altering the axis of rotation of the propellers.

2. Apparatus for lifting or sustaining a flying machine by the expansive forces produced by mutual impact of opposing streams of compressed air, comprising non-feathering propellers arranged well towards one end of the body, mountings therefor, each propeller

consisting of a plurality of blades rotating about a fixed axis with the inner and outer edges of the blades sweeping through conical paths so as to produce streams of compressed air, which streams are opposed in pairs and create expansive forces by mutual impact beneath the fuselage of the machine, means for rotating said propellers, and means for moving one propeller backward or forward to a greater extent than the other to effect steering in the horizontal plane.

3. Apparatus for lifting or sustaining a flying machine by the expansive forces produced by mutual impact of opposing streams of compressed air, comprising non-feathering propellers arranged well towards one end of the body, mountings therefor, each propeller consisting of a plurality of blades rotating about a fixed axis with the inner and outer edges of the blades sweeping through conical paths so as to produce streams of compressed air, which streams are opposed in pairs and create expansive forces by mutual impact beneath the fuselage of the machine, each blade substantially following the contour of the wings of the common drone-fly (*Eristalis tenax*); and means for rotating said propellers.

In testimony whereof, I affix my signature,
30 THOMAS AUGUSTUS DRING.
